UNITED STATES PATENT OFFICE

157,582

VENDING MACHINE

Chester A. Frick, Glendale, Calif., assignor to Leo
M. Harvey, Los Angeles, Calif.

Application June 6, 1949, Serial No. 3,084

Term of patent 14 years

(Cl. D52—3)

To all whom it may concern:

Be it known that I, Chester A. Frick, a citizen of the United States, residing in the city of Glendale, county of Los Angeles, and State of California, have invented a new, original, and ornamental Design for a Vending Machine, of which the following is a specification, reference being had to the accompanying drawings, forming a part thereof.

Fig. 1 is a perspective view of a vending machine showing my new design, showing the front and one side, Fig. 2 is a perspective view showing the back, the other side and the bottom, and Fig. 3 is a plan view of the vending machine.

I claim:

The ornamental design for a vending machine, as shown.

CHESTER A. FRICK.
